UNITED STATES PATENT OFFICE

STEPHEN M. MARTIN, OF BRIDGEPORT, CONNECTICUT, ASSIGNOR, BY MESNE ASSIGNMENTS, TO JULIUS F. HOLMES, OF NEW YORK, N. Y.

MECHANICAL REFRIGERATING SYSTEM

Application filed December 31, 1928. Serial No. 329,482.

This invention relates to mechanical refrigeration systems and particularly to chilling units for use in the same.

This invention has for its object generally the provision of a device of the character specified, which is efficient, economical and readily manufactured.

More specifically it is an object to provide a chilling unit which has a high heat absorption capacity and also has a sufficient bulk of metal maintained at a relatively low temperature so that the use of brine as a storage medium for maintaining a constant low temperature is unnecessary.

It is also an object to provide a chilling unit which is rugged, readily machined, and is readily put in place and removable from refrigerator casings.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claim.

For a fuller understanding of the nature and objects of the invention reference should be had to the following detailed description taken in connection with the accompanying drawings, in which:

Fig. 1 is a view, partly in section and partly in elevation, showing a chilling unit installed in a refrigerator casing in accordance with the present invention;

Fig. 2 is a vertical cross-sectional view of the chilling unit and refrigerator casing shown in Fig. 1, taken on the line 2-2 in Fig. 3;

Fig. 3 is a top plan view of the chilling unit shown in Fig. 1;

Fig. 4 is another vertical cross-section of the chilling unit shown in Fig. 1, but taken in a plane at right angles to that shown in Fig. 2;

Fig. 5 is a fragmentary view, similar to Fig. 4, which shows a modified form of chilling unit; and

Fig. 6 is a rear elevation of the chilling unit shown in Fig. 5.

Referring now to the drawings and particularly to Fig. 1, 10 denotes a refrigerator casing having an insulating side wall 11 and a top wall 12 enclosing a chilling space. The top wall 12 is provided with a plurality of securing means 13 depending from the inside surface of the top wall into the chilling space. These securing means may be of any convenient form, for example, threaded bolts secured in the insulating wall and depending into the chilling space so as to have their shanks detachably connected to supporting block 14 by which the chilling unit 15 is suspended in the chilling space.

The chilling unit 15 here shown comprises a metallic box-like structure of double-walled construction, the double walls being shown at 16 and 17 respectively in Fig. 2. From Fig. 4 it is also seen that the double walls extend across the rear of the chilling unit but are absent from the front so that the unit encloses a secondary chilling space 18 accessible only from the front.

A plurality of horizontal partitions, as shown by 19, preferably are inserted and extend across the secondary chilling space dividing the space into horizontal sections that are adapted to receive ice drawers 20 insertable from the front. These ice drawers are adapted to provide a supply of ice cubes or the like when a freezing temperature is maintained within the secondary chilling space 18.

The double-walled chilling unit 15, as shown in Fig. 4 is an integral casting which has an opening at 21 in its exterior lower wall through which cooled refrigerant or working fluid is supplied by means of a suitable pipe connection, as shown at 22. A second opening 23 is preferably provided in this lower wall at a distance from the first. This opening provides an alternative place at which the inlet connection may be attached. These openings 21 and 23 provide cleaning places through which the sand of the core employed when casting the unit may be readily removed, as it is desired to have a relatively clean casting for service of the character indicated in the mechanical refrigerating systems. A third opening in the casting is provided at 24 in the rear wall near its

upper edge. This opening is positioned at the height at which it is desired to maintain the liquid level of the refrigerant or working fluid in the evaporating space between the walls of the chilling unit. In this opening 24 is secured an outlet pipe connection as shown in 25.

The integral casting here shown is also provided with an opening 26 in the rear wall 10 which is a thru-opening to the secondary chilling space 18, this opening having an annular wall 27 bounding the same and joining both the inner and outer rear walls of the chilling unit. This opening is provided

15 as a matter of convenience and provides good support to the interior cores when casting the integral unit here shown. The opening at 26 is preferably closed and for this purpose has a plug inserted as indicated at 28.

20 The casting comprising the chilling unit herein employed is of metal, having relatively good heat conductivity. A suitable metal is, for example, cast iron, aluminum, copper, or an alloy thereof. The walls of the casting 25 are relatively thick in order that the unit may provide a "storage effect" in lieu of brine and thus have a relatively large body of metal with a relatively good specific heat that is maintained at a low temperature within the

30 chilling space of the refrigerator. The walls of this chilling unit are preferably plain as the heat flow therethrough is more uniform and a uniform temperature differential on opposite sides of the walls is to be maintained.

35 As it is desired to maintain a temperature at the surface of the exterior wall of the chilling unit which is substantially constant, it is desired that the means which control the circulation of refrigerant or working fluid 40 through the evaporating space of the chilling unit shall be located on its exterior wall. A convenient location for this purpose is on the rear wall of the chilling unit, the means for supporting the control device being here

45 shown in the form of a wedge-shaped bracket 29 cast integrally upon the rear wall. This bracket may be machined and provided with suitable openings, as shown at 30 in Fig. 6, by which the control means is secured. The 50 evaporating space of the chilling unit 15 is, of course, hermetically sealed, and all openings through its walls which do not have pipe connections secured therein are closed by suitable means, for example, by plugs as shown at 55 23' in Fig. 4.

The means for securing the chilling unit of the present invention in the refrigerator casting are of a character which can readily be manipulated from the front of the refrigerator casing when the door 11' is swung open. The supporting blocks 14, as shown in Fig. 4, are preferably in the form of rectangular frames having open sides (see Fig. 3) through which the ends of bolts and nuts are accessible for manipulation. The shanks of the

bolts 13 are arranged to extend down through the top members 141 of the supporting blocks and have on their lower ends nuts 142 which engage with the threads and bear up against the top members 141. Also, there are bolts 143 inserted at the sides of the blocks and pass through the lower members 144 thereof and are made to engage by means of their screw threads with upstanding lugs 150 projecting up from the top wall of the chilling unit 15. Four lugs 150 are shown, a less number, however, may be used, as is well understood.

In assembly it is seen that after the castings for the chilling unit have been cleaned and machined and have their openings, which are not to be used in the circulation of refrigerant, properly closed, are first made ready by attaching supporting blocks 14 to the lugs 150 prior to the chilling units being suspended from the top of the refrigerator casing. In order to suspend the chilling unit in place it is raised to a position in the refrigerator casing such that the depending bolts 13 pass through the top members 141 of the supporting blocks 14, whereupon nuts 142 are slipped into place and screwed into engagement with the projecting ends of bolts 13. The pipe connections may then be made, the control means secured to bracket 29, and the ice drawers 20 slipped into place.

While in Fig. 1 to Fig. 4 a chilling unit that is an integral casting is shown, it is also contemplated that a casting may be employed which is not integral but is assembled so as to have substantially the thermal characteristics of the chilling unit herein shown. A modified arrangement for this purpose is shown in Fig. 5 and 6. Here the chilling unit 15, as originally cast, does not have a rear wall, but has a separable rear end wall or plate 160 in the form of a cast plate that is adapted to be secured to the casing in a fluid-tight manner. This fluid-tight closure may be accomplished in any well known manner; for example by the insertion of a flexible, malleable metallic gasket 161 between the unit and the plate 160. Suitable metallic gaskets for this purpose are made of lead and when interposed between the plate 160 and the end portion, the chilling unit forms a fluid-tight connection. The means for securing the plate 160 is shown as comprising a plurality of bolts 162 which pass through the plate 160 and engage with cooperating recesses 163 formed as strengthening ribs 164 about the open side wall portions of the unit.

The chilling unit thus provided may be more readily cleaned than the chilling unit shown in Figs. 1 to 4, since the area of the opening through which access is had to the interior of the evaporating space is materially greater. The plate 160 is shown as provided with a bracket 29 for supporting the control device.

The chilling unit of the present invention is also preferably provided with means for determining when the refrigerating system of which it forms a part has been properly 5 filled with cooled refrigerant or working fluid. Simple means for this purpose comprise an air cock 170 which is inserted in an opening in a side wall of the chilling unit at the elevation at which the liquid level is desired to be maintained. This air cock 170 10 may be of the ordinary key-operated variety and so located as to be readily accessible from the front refrigerator casing when the door 11' is open. A convenient location of the air 15 cock 170 is illustrated in Figs. 1 and 3. When the refrigerating system is to be charged with working fluid, the cock 170 is opened with the key so that air may escape while refrigerant or working fluid is flowing into the system. 20 When sufficient refrigerant or working fluid has passed into the system, and the desired liquid level in the chilling unit has been attained, refrigerant will begin to run out of the cock 170. Whereupon the cock 170 is 25 closed and the charging of the system discontinued, the system thereafter being hermetically sealed.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

In a mechanical refrigerating system, a 40 chilling unit comprising a substantially plain double-walled metallic casting, said walls being shaped to be reentrant and enclosing a relatively narrow evaporating space, said casting having a prismatic form, the reentrant walls being arranged to envelope a secondary chilling space entered from a side of the casting, the exterior walls being provided with openings, circulating connections being attached to certain of said openings, 45 means for indicating when the system is properly filled in another of said openings, upstanding thickened wall members being disposed over the top and sides of said casting, certain of which are provided with attaching means whereby said casting may be suspended in a refrigerating box, and other thickened wall formations on the exterior of said casting whereby auxiliary mechanisms 55 may be attached.

60 In testimony whereof I affix my signature.
STEPHEN M. MARTIN.
